UNITED STATES PATENT OFFICE

1,921,342

EGG BEATER

Porter K. Bushnell, Berkeley, Calif.

Application December 16, 1931. Serial No. 581,492

3 Claims. (Cl. 259—131)

My invention relates to improvements in egg beaters, and it consists of the combinations, constructions and arrangements hereinafter described and claimed.

5 An object of my invention is to provide an improvement over my patent on an egg beater, Patent No. 1,742,230, issued January 7, 1930. In the patent, I showed beating elements carried by shanks, which were removably secured to 10 a body portion. In the present invention, I show a similar arrangement, but provide stops for limiting the movement of the shanks in the supporting sleeves. The stops are carried by a bracket, which, in turn, is secured to the body portion. 15 The body portion is supported by a handle, which is secured thereto.

Another feature of the invention lies in the hinging of the beaters so that the pairs of beaters can first be removed from the shanks and then 20 the beaters in each pair be swung into open position so as to be readily cleaned.

Other objects and advantages will appear in the following specification, and the novel features of the device will be particularly pointed out in 25 the appended claims.

My invention is illustrated in the accompanying drawing forming a part of this application, in which

Figure 1 is a front elevation of the device; 30 Figure 2 is a side elevation of the upper portion of the beater;

Figure 3 is a section along line 3—3 of Figure 1;

Figure 4 is a section along line 4—4 of Figure 1;

Figure 5 shows one set of beaters; and

Figure 6 is an enlarged sectional view of a part of the device.

In carrying out my invention, I provide a body 40 portion 1, to which I secure a handle 2 of the shape shown. A bracket 3 is carried by the body portion 1 and has ears 4 for supporting a stub shaft 5.

A driving gear 6 is mounted on the shaft 5 and is manually rotated by means of a handle 7. The gear 6 is designed to mesh with a small bevel gear 8, and the gear 8 is designed to mesh with another small bevel gear 9.

I will now describe the construction of one of 50 the sets of beating members and then will show how the two sets of beating members are removably disposed on shanks which, in turn, are removably secured to the body portion 1. In Figures 5 and 6, I show a U-shaped beating element 10, having its leg portions 11 riveted, or

otherwise secured to the gear 8. The U-shaped portion of the element 10 is circular in shape, as shown at 12. A U-shaped bracket 13 is also secured to the gear 8 and in turn is pivotally secured at 14 to legs 15 of the second U-shaped 60 beater element, indicated generally at 16. Figure 4 shows the element 16 swung at right angles to the element 10, and this exposes the surfaces so that they can be readily cleaned. The element 16 has a projection 17, with an opening therein, 65 that is removably received in an eyelet 18 in the member 10. The members 10 and 16 have enough spring quality to cause the projection 17 to snap into place when registering with the eyelet 18, (see Figure 6). In this way, the members 10 70 and 16 are held in adjusted position.

A U-shaped support 19 has shanks 20, and these shanks are passed through registering eyelets 17 and 18 and through openings in the gears 8 and 9. The shanks project above the gears 8 and 9 and 75 are received in sleeves 21 that are formed from portions of the body 1.

The sleeves have slots 22 therein, and a spring-pressed keeper 23 has catches 24 for entering notches 25 in the shanks 20. The keeper 23 is 80 carried by a spring-pressed rod 26, and the rod, in turn, is provided with a push button 27.

In order to properly position the notches 25 with respect to the slots 22, I provide stops 28 on the bracket 3, and these stops limit the movement 85 of the shanks 20 in the sleeves 21. When the notches 25 are in registration with the slots 22, a spring 29 will move the keeper 23 so as to secure the shanks to the body portion. The device is 90 now ready for use.

From the foregoing description of the various parts of the device, the operation thereof may be readily understood.

The egg beater can be used in the usual manner, and when the operator wishes to clean it, the push button 27 is depressed, and this frees the shanks 20. The pairs of beating elements 30 can now be removed and the elements of each pair can be 95 swung apart, as shown in Figure 5, for ready cleaning. After cleaning, the device can be re-assembled in the manner already described.

While I have shown only the preferred form of my invention, it should be understood that various changes or modifications may be made within the scope of the appended claims without departing from the spirit of the invention.

I claim:

1. In an egg beater, a U-shaped beating element having its shanks secured together, and a recess 100 in its U-shaped end, a second U-shaped beating 110

- element having its shanks hinged to the shank ends of the first element and in right angle relation thereto and having a projection in its U-shaped end removably receivable in the recess. 80
- 5 2. In an egg beater, a U-shaped beating element having its shanks secured together, and a recess in its U-shaped end, a second U-shaped beating element having its shanks hinged to the shank ends of the first element and in right angle relation thereto and having a projection in its U-shaped end removably receivable in the recess, 85

the wall of the recess and the projection having openings designed to register for receiving the shank of a supporting member.

3. In an egg beater, a pair of symmetrical U-shaped beating elements mounted for rotary movement about a common axis passing between the shanks, one element being arranged at right angles to the other and being hingedly secured thereto at the shank ends of the elements. 90
